UNITED STATES PATENT OFFICE

JOHN H. SHAW, OF NEW HAVEN, CONNECTICUT, ASSIGNOR TO SARGENT & COMPANY, OF NEW HAVEN, CONNECTICUT

LOCK

Application filed March 7, 1929. Serial No. 344,974.

My invention relates to locks and more especially to locks in which the locking mechanism may be adjusted from the inside of a door to prevent manipulation of the mechanism from the exterior of the door.

The invention relates particularly to a very simple and efficient lock of the above character.

In a more specific aspect, the invention relates to knob locks and one of the objects of the invention is to provide an improved construction of this character which may be readily manipulated to operate the lock mechanism.

Another object of the invention is to provide a knob lock which may be rendered inoperative from the interior of a door against manipulation by an ordinary or change key.

A further object of the invention is to provide a lock of the above character which may be readily restored to normal operative position by a master key.

To these and other ends, the invention consists in the novel features and combination of parts to be hereinafter described and claimed.

In the drawings,

Fig. 1 is a fragmentary view of a door showing a lock according to my invention mounted therein;

Fig. 2 is an end view of the door and lock shown in Fig. 1;

Fig. 3 is a sectional view along line 3—3 of Fig. 1;

Fig. 4 is a view similar to Fig. 3 but showing the lock parts in a different position;

Fig. 5 is a sectional view along line 5—5 of Fig. 3;

Fig. 6 is a sectional view along line 6—6 of Fig. 3;

Fig. 7 is a sectional view along line 7—7 of Fig. 3;

Fig. 8 is a sectional view along line 8—8 of Fig. 3;

Fig. 9 is a sectional view along line 9—9 of Fig. 4;

Fig. 10 is a sectional view along line 10—10 of Fig. 4; and

Fig. 11 is a sectional view along line 11—11 of Fig. 4.

Referring to the drawings in which I have illustrated my invention by showing a preferred embodiment of the same, the reference numeral 15 indicates a part of a door in which is mounted my improved lock generally designated by the reference numeral 16. The lock 16 comprises a case or frame 17 in which is mounted a transversely extending tube 18, in one end of which is received the shank 19 of knob 20, while in the opposite end is shank 21 of knob 22. Shank 19 of knob 20 is free to rotate in tube 18 and at its inner end 23 is counterbored and transversely slotted, as at 24, for the reception of arms 25 and 26 of rollback 27, arms 25 and 26 engaging abutments 28 and 29 on yoke 30, yoke 30 having a stem 31 which passes through an interior wall 32 of frame 17 and is pivotally secured to the latch bolt 33, the latter being pivotally mounted in face plate 34 by means of pivot pin 35. Latch bolt 33 is constantly urged into protracted position by means of compression spring 36 mounted on and surrounding stem 31 between wall 32 and latch bolt 33.

Tube 18 and shank 21 are secured against movement in lock frame 17 by screw 37 which passes through a part of the frame through tube 18 and into shank 21 (Figure 10). Axial movement of tube 18 and shanks 19 and 21 is prevented by keepers 38 and 39 which pass through suitable openings in the lock frame 17 and tube 18 and into circumferential grooves 40 and 41 of shanks 19 and 21, respectively.

Mounted in the knob 22 is a cylinder lock 42 having a key plug 43, the movement of which is controlled by pin tumblers 44, key plug 43 having a shank 45 on which a thimble 46 is mounted, thimble 46 being secured to shank 45 by means of pin 47. Received in a preferably square opening in the end 48 of thimble 46 is a square rod 49 having mounted thereon a rollback 50 provided with arms 51 and 52, which engage abutments 28 and 29, to retract bolt 33 in a manner similar to the rollback arms 25 and 26.

Mounted for axial reciprocation in the knob shank 19 is a rod 53 having a button-like head or end 54 which extends outwardly through knob 20, rod 53 being urged axially outwardly in shank 19 by compression spring 55, mounted on and surrounding rod 53, one end of spring 55 bearing against head 54, while the opposite end bears against a part of the knob. Rod 53 is axially bored at 56 for the reception of a stem 57 on the end of rod 49, stem 57 being free to reciprocate and rotate in bore 56. At the opposite end of rod 49 from stem 57 is a compression spring 58, one end of which is received in an axial opening 59 in rod 49, while the opposite end bears against a disc 60 in thimble 46. Rod 49 adjacent its end is provided with an annular groove 61 which may be brought opposite the end 48 of thimble 46 by pressing button or head 54 of rod 53 inwardly. In this position of rod 49 the key plug 43 may be rotated without producing rotation in the rod.

In order that the lock parts may be held in this position, a transversely movable dog 62 is mounted on rod 53, dog 62 in the particular instance illustrated being substantially U-shaped and provided with legs 63 and 64, which straddle a central part of rod 53 and are received in slots disposed at diametrically opposite points in rod 53. Dog 62 is constantly urged radially outwardly by spring 65 which may be conveniently disposed in groove 66 in rod 53, and which in the preferred embodiment illustrated is provided with an end 67 bent at right angles to the main part of the spring and disposed in an opening 68 in rod 53.

The normal position of dog 62 is shown in Figs. 3 and 8. Upon the button 54 being pushed inwardly in knob 20, the dog 62 is brought opposite a radially directed opening 69 in tube 18 into which the dog is forced by spring 65, whereupon the rod 53 is held against axial movement with the end 48 of thimble 46 opposite groove 61. It will be readily understood that in this position the latch bolt cannot be retracted from the exterior of the door by inserting the ordinary change key 70 in key plug 43 and rotating the latter.

In order that the lock mechanism may be restored to normal position, an abutment 71 is provided on yoke 30, abutment 71 being received in opening 69 during the retraction and protraction of the latch bolt. Dog 62 is provided with a curved convex head 72 which may be engaged by abutment 71 as the latter moves through opening 69, engagement of head 72 with abutment 71 forcing the latter upwardly into the rod 53 until the dog 62 is received wholly within the axial opening in shank 19; whereupon rod 53 is free to move outwardly under

the urge of spring 55 to permit spring 58 to force the square end of rod 49 through the square opening in thimble end 48. Movement of rod 53 is limited by pin 73 mounted in shank 19 and passing transversely through slot 74 in rod 53.

In order that the latch may be retracted from the exterior of the door when the button is held inwardly by dog 62 and thimble end 48 is opposite groove 61, a second thimble 75 is provided, mounted on and surrounding thimble 46, thimble 75 being free to rotate on thimble 46 and having an end 76 provided with a square opening in which rod 49 is received beyond groove 61. Thimble 75 is mounted in a counterbored opening 77 in shank 21 being held against axial movement in bore 77 by shoulder 78 on shank 21 and flange 79 on thimble 46. Thimble 75 is provided with an axially directed slot 80 which is normally in alignment with the key slot 81 of key plug 43, whereby a master key 82 may be inserted in the key plug, the extended end 83 of the master key being received in slot 80 and rotating thimble 75 upon rotation of key plug 43.

The operation of my improved lock may be readily understood from the above description by one skilled in the art, but may be briefly described as follows:

The normal position of the lock mechanism is shown in Figure 3, wherein knob 20 may be rotated to retract the latch bolt 33 through the engagement of rollback 27 with yoke 30, or the latch 33 may be retracted by rotation of key plug 43 upon the insertion of a suitable key 70, latch 33 being retracted in this instance by means of rollback 50 mounted on square rod 49 which is received in the end 48 of thimble 46 secured to the key plug 43 by means of pin 47. When one at the interior of the door desires to secure the latch against retraction by means of the ordinary key 70, the button 54 is pressed inwardly to move rod 49 in the direction of key plug 43 until the end 48 of thimble 46 is opposite the groove 61 in rod 49. In this position, the spring 65 urges dog 62 radially outwardly into opening 69 in tube 18, locking rod 53 in its inner position and rendering the cylinder lock 42 inoperative to retract the latch bolt by the use of the ordinary key 70.

In order that the occupant of the room may not lock himself out, means is provided for releasing the button 54 in rod 49 upon the door being opened, this means in the present instance comprising an abutment 71 on yoke 30, which, upon retraction of the latch bolt by the knob 20, engages dog 62 and forces the latter radially inwardly until the dog is wholly received within the axial bore of shank 19, whereupon the spring 55 moves the rod 53 and button 54 axially out-

wardly and permits spring 58 to move rod 49 inwardly to bring the square end of rod 49 into the opening in thimble end 46, whereupon the latch may be retracted by the 5 usual key 70, as will be readily understood.

In order that the latch bolt may be retracted from the exterior of the door when the button 54 is secured in its innermost position by dog 62, a master key 82 may be 10 inserted in key plug 43, master key 82 having an extended end 83 which is received in the slot 80, in thimble 75 rotation of master key 82 producing rotation in rod 49 through thimble 75, and thus the retraction of the 15 latch bolt. It will be readily understood that the dog 62 is released from opening 69 by the abutment 71 upon the retraction of the latch bolt by the master key.

From the above description of the nature 20 of my improved lock and its mode of operation, it will be readily understood that I have provided a relatively simple form of locking mechanism in which a latch retracting mechanism may be secured from the 25 interior of the room against retraction by the usual change key at the exterior of the room, the mechanism being such, however, that the latch may be retracted at all times by the use of a master key received in the 30 lock mechanism at the exterior of the door.

While I have shown and described a preferred embodiment of my invention, it will be understood that the same is not to be limited to all the details shown, but is capable 35 of modification and variation within the spirit of the invention and the scope of the appended claims.

What I claim is:

1. In a door lock, a latch bolt, operating 40 mechanism therefor, a knob on one side of said lock for actuating said operating mechanism and a key operated member on the other side of the lock for actuating said mechanism, said key operated member being 45 adapted to receive a change key and a master key, means on the opposite side of the lock from said key operated member for disengaging the key operated member from connection with said mechanism for operation thereof by the change key, whereby 50 when the change key is received in said lock it will rotate idly, and means controllable by the master key controlled member for restoring the engagement of the key controlled member with said operating mechanism.

2. In a door lock, a latch bolt, operating 55 mechanism for said latch bolt, knobs, one on either side of said lock, one of said knobs being connected to said mechanism and adapted to actuate the same and the other of said knobs having a cylinder lock therein, means normally connecting said mechanism to said cylinder lock whereby the mechanism 60 may be actuated by the cylinder lock upon

the insertion of a proper key means on the lock case on the same side as the first mentioned knob for disengaging said cylinder lock from operative connection with the operating mechanism, and means operable by 70 a key inserted in the cylinder lock for restoring the normal connection of the latter to the retracting mechanism.

3. In a door lock, a latch bolt, operating 75 mechanism for said latch bolt, a knob on one side of said lock for actuating said operating mechanism, key controlled means on the other side of said lock for actuating the operating mechanism, a button on the same side as said knob for disengaging the key controlled means from operative engagement 80 with the operating mechanism, and means controllable by the retraction of the latch bolt for restoring the engagement of the key controlled means with the operating mechanism.

4. In a door lock, a latch bolt, operating 85 mechanism therefor, members positioned on opposite sides of said lock for actuating said operating mechanism, the member on one side of said lock comprising key operated means, means on the other side of the lock to disengage said key operated means from engagement with said mechanism, whereby 90 the key operated means may operate idly, and means controllable by the retraction of the latch bolt for restoring the engagement of said key operated means with said operating mechanism.

5. In a door lock, a latch bolt, operating 95 mechanism for said latch bolt, knobs one on either side of said lock, one of said knobs being connected to said mechanism and adapted to actuate the same and the other of said knobs having a cylinder lock therein normally connected to said mechanism and adapted to actuate the same, means on the lock case on the same side as the first mentioned knob for disengaging said cylinder lock from operative connection with the operating mechanism, and means controllable by the movement of the latch operating mechanism upon retraction of the latch for restoring the engagement of the cylinder lock with the operating mechanism.

6. In a door lock, a latch bolt, operating 100 mechanism for said latch bolt, knobs one on either side of said lock, one of said knobs being connected to said mechanism and adapted to actuate the same, and the other of said knobs having a cylinder lock therein normally connected to said mechanism and adapted to actuate the same, a button in the first mentioned knob, means controlled by said button for disengaging the cylinder lock from operative connection with the operating mechanism, and means controllable by a part of the latch operating mechanism 105 upon retraction of the latch for restoring 110 115 120 125 130

the engagement of the cylinder lock with the operating mechanism.

7. In a door lock, a latch bolt, operating mechanism for said latch bolt, a knob on one side of said lock for actuating said operating mechanism, key operated means on the other side of said lock, said means being adapted to actuate the operating mechanism upon the insertion of a change key, means on the lock on the same side as said knob for disengaging the key operated means from operative engagement with the operating mechanism, and means operable by a master key received in said key operated means for restoring the engagement of said key operated means with the operating mechanism.

8. In a door lock, a latch bolt, operating mechanism for said latch bolt, a knob on one side of said lock for actuating said operating mechanism, key operated means on the other side of said lock for actuating the operating mechanism upon the insertion of a change key, a button on the same side as said knob for disengaging the key operated means from engagement with the operating mechanism for actuation by the change key, means engageable by a master key received in said key operated means for operating said latch mechanism, and means controllable by the retraction of the latch bolt for restoring the engagement of said key operated means with the operating mechanism for operation by the change key.

9. In a door lock, a latch bolt, operating mechanism for said latch bolt, knobs one on either side of said lock, one of said knobs being connected to said mechanism and adapted to actuate the same, and the other of said knobs having a cylinder lock therein normally connected to said mechanism and adapted to actuate the same, a button in the first mentioned knob, means controlled by said button for disengaging the cylinder lock from normal operative connection with the operating mechanism, means engageable by a master key received in the cylinder lock for retracting the latch bolt, and means controllable by the retraction of the latch bolt for restoring the engagement of the cylinder lock with the operating mechanism.

10. In a door lock, a latch bolt, operating mechanism for said latch bolt, a knob on one side of said lock for actuating the operating mechanism, key operated means on the other side of said lock for actuating the operating mechanism, and means for disengaging said key operated means from normal operative engagement with the operating mechanism, said disengaging means comprising a movable rod mounted for reciprocation in said knob, a second rod engageable by said first named rod and mounted for movement relatively to said key operated means, and means on the end of the second rod for en-

gaging a part of the key operated means to permit operation of the operating mechanism by the key operated means.

11. In a door lock, a latch bolt, retracting mechanism therefor, a knob on one side of said lock for actuating said retracting mechanism, and a key operated member on the other side of the lock for actuating said mechanism, said key operated member being adapted to receive a change key and a master key, means on the opposite side of the lock from the key operated member for disengaging the key operated member from connection with said mechanism for operation thereof by the change key, and means controllable by the master key when inserted in said key operated member for restoring the engagement of the key operated member with said operating mechanism for operation thereof by the change key.

12. In a door lock, a latch bolt, retracting mechanism for said latch bolt, a knob on one side of said lock for actuating said retracting mechanism, key operated means on the other side of said lock, said means being adapted to actuate the retracting mechanism upon the insertion of a change key in the key operated means, means on the lock on the same side as said knob for preventing the operation of the retracting mechanism by means of the change key, and means operable by a master key received in said key operated means for restoring said key operated means to change key operable condition.

13. In a door lock, a latch bolt, retracting mechanism for said latch bolt, key operated means on one side of said lock for actuating the retracting mechanism, a depressible button on the opposite side of said lock from the key operated means, said button being adapted upon depression to disengage the key operated means from operative engagement with the retracting mechanism, means for holding said button in depressed position, and means operable by the retraction of the latch bolt for releasing said button holding means.

14. In a door lock, a latch bolt, retracting mechanism for said latch bolt, a key operated member, a connection between the key operated member and the retracting mechanism, means for interrupting the connection between the key operated member and the retracting mechanism, and means controlled by the movement of the latch bolt for restoring the connection between the member and the retracting mechanism.

15. In a door lock, a latch bolt, retracting mechanism for said latch bolt, key operated means on one side of said lock for actuating the retracting mechanism, a plurality of connections between said key operated means and said retracting mechanism, one of said connections being operable by a change key and the other by a master key,

and means on the other side of the door from said key operated means for disengaging one of said connections from operative engagement with the retracting mechanism.

5 16. In a door lock, a latch bolt, retracting mechanism for said latch bolt, key operated means on one side of said lock for actuating the retracting mechanism, a plurality of connections between said key operated means and said retracting mechanism, one of said connections being operable by a change key and the other by a master key, and means on the other side of the door from said key operated means for disengaging 10 one of said connections from operative engagement with the retracting mechanism, and means operative upon retraction of the latch bolt for restoring said connection to operative engagement with the retracting 15 mechanism.

20 17. In a door lock, a latch bolt, retracting mechanism for said latch bolt, key operated means on one side of said lock for actuating the retracting mechanism, said key operated means including a plurality of connections with said retracting mechanism, one of said connections being operable by a change key and the other by a master key, means on the other side of the door from the key operated 25 means for disengaging the change key operable connection from engagement with the retracting mechanism, and means operable upon the retraction of the latch bolt for restoring said connection to operative engagement with the retracting mechanism.

30 18. In a door lock, a latch bolt, retracting mechanism for said latch bolt, operating members for said retracting mechanism one on either side of said lock, said operating 40 members having means extending into the lock for actuating said retracting mechanism, the means on one of said members extending into and being axially movable in the means extending into the retracting 45 mechanism from the other operating member, said axially movable means having an operative engagement with its respective operating member in one position of axial movement, and being free from operation 50 thereby in another position of the axial movement.

55 19. In a door lock, a latch bolt, retracting mechanism for said latch bolt, a knob at the interior of the door having a stem extending into and in operative engagement with the retracting mechanism, means at the other side of said door for operating said retracting mechanism, said means including an axially movable rod extending 60 into the stem of said knob, said rod having an operative engagement with a part of the retracting mechanism and being normally in operative engagement with its operating means, and axially movable means mounted 65 in said knob and engaging said rod to move

the latter into position to disengage it from its operating means.

20. In a door lock, a latch bolt, retracting mechanism for said latch bolt, a knob at the interior of the door having a stem 70 extending into and in operative engagement with the retracting mechanism, means at the exterior side of said door for operating said retracting mechanism, said means including an axially movable rod extending into the stem of said knob, said rod having an operative engagement with a part of the retracting mechanism and being normally in operative engagement with the means at the exterior of the door, and an axially movable 75 rod mounted in said knob and engaging said first named rod to move the latter into position wherein it is disengaged from the means at the exterior of the door.

21. In a door lock, a latch bolt, retracting mechanism for said latch bolt, a knob at the interior of the door having a stem extending into and in operative engagement with the retracting mechanism, means at the other side of said door for operating said 80 retracting mechanism, said means including an axially movable rod extending into the stem of said knob, said rod having an operative engagement with a part of the retracting mechanism and being normally in operative engagement with its operating means, and an axially movable rod mounted in said knob and engaging said first named 85 rod to move the latter into position wherein it is disengaged from its operating means, a radially movable dog associated with said second named rod, means engaging said dog upon movement of the rod into disengaging 90 position to hold the rod against movement, and means on a part of the latch mechanism 95 mounted in said knob for releasing the dog upon movement of the latch bolt.

22. In a door lock, a latch bolt, operating mechanism for said latch bolt, a knob on one side of the lock for actuating said operating 100 mechanism, key operated means on the other side of said lock for actuating the operating mechanism, a thimble on the inner end of said key operating means, an axially movable shaft mounted in said thimble and extending into the operating mechanism, said shaft having a non-circular part and a circular part, said thimble having a part normally embracing the non-circular part of the shaft, and means for moving said shaft 115 to bring the circular part thereof opposite the said part of the thimble.

23. In a door lock, a latch bolt, operating mechanism for said latch bolt, a knob on one side of the lock for actuating said operating 120 mechanism, key operated means on the other side of said lock for actuating the operating mechanism, a thimble on the inner end of said key operated means, an axially movable shaft mounted in said thimble and extend- 125 130

- ing into the operating mechanism, said shaft having a non-circular part and a circular part, said thimble having a part normally embracing the non-circular part of the shaft, and means for moving said shaft to bring the circular part thereof opposite the said part of the thimble, said last named means comprising an element extending through the knob.
24. In a door lock, a latch bolt, operating mechanism for said latch bolt, a knob on one side of the lock for actuating said operating mechanism, key operated means on the other side of said lock for actuating the operating mechanism, a thimble on the inner end of said key operated means, an axially movable shaft mounted in said thimble and extending into the operating mechanism, said shaft having a non-circular part and a circular part, said thimble having a part normally embracing the non-circular part of the shaft, and means for moving said shaft to bring the circular part thereof opposite the said part of the thimble, said last named means comprising an element extending through the knob, and a dog associated with the shaft moving means adapted to hold the shaft in one position of axial movement.
25. In a door lock, a latch bolt, operating mechanism for said latch bolt, a knob on one side of the lock for actuating said operating mechanism, key operated means on the other side of said lock for actuating the operating mechanism, a thimble on the inner end of said key operated means, an axially movable shaft mounted in said thimble and extending into the operating mechanism, said shaft having a non-circular part and a circular part, said thimble having a part normally embracing the non-circular part of the shaft, and means for moving said shaft to bring the circular part thereof opposite the said part of the thimble, said last named means comprising an element extending through the knob, and means actuated by retraction of the latch bolt for releasing said dog.
26. In a door lock, a latch bolt, operating mechanism for said latch bolt, a knob on one side of the lock for actuating said operating mechanism, key operated means on the other side of the lock for actuating the operating mechanism, a thimble on the inner end of said key operated means, an axially movable shaft mounted in said thimble and extending into the operating mechanism, said shaft having a non-circular part and a circular part, said thimble having a part normally embracing the non-circular part of the shaft, means for moving said shaft to bring the circular part thereof opposite the said part of the thimble, and means associated with the key operated means for rotating said shaft in the last named position thereof.

27. In a door lock, a latch bolt, operating mechanism for said latch bolt, a knob on one side of the lock for actuating said operating mechanism, key operated means on the other side of the lock for actuating the operating mechanism, a thimble on the inner end of said key operated means, an axially movable shaft mounted in said thimble and extending into the operating mechanism, said shaft having a non-circular part and a circular part, said thimble having a part normally embracing the non-circular part of the shaft, means for moving said shaft to bring the circular part thereof opposite the said part of the thimble, and means associated with key operated means for rotating said shaft in either of said positions.

In witness whereof, I have hereunto set my hand this 14th day of February, 1929.

CERTIFICATE OF CORRECTION.

Patent No. 1,902,343.

March 21, 1933.

JOHN H. SHAW.

It is hereby certified that error appears in the printed specification of the above numbered patent requiring correction as follows: Page 3, line 53, claim 1, strike out the words "controlled member", and line 56, same claim, after the syllable "anism" insert the words "for operation thereof by the change key"; and that the said Letters Patent should be read with these corrections therein that the same may conform to the record of the case in the Patent Office.

Signed and sealed this 16th day of May, A. D. 1933 **M. J. Moore.**

(Seal)

Acting Commissioner of Patents.
